Primary Examiner — Randall Gholson(74) *Attorney, Agent, or Firm* — NSIP Law(57) **CLAIM**

We claim the ornamental design for a stand for television receiver, as shown and described.

DESCRIPTION

FIG. 1 is a front perspective view of a stand for television receiver showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a perspective view of the stand for television receiver in which a television receiver is provided in broken lines to illustrate an example environment.

The broken lines in the figures depict environmental subject matter and form no part of the claimed design.

The dot-dash broken lines define the boundaries of the claimed design and form no part thereof.
